GUARD FOR TOMATO LUGS AND SIMILAR CONTAINERS

Original Filed Nov. 7, 1933

UNITED STATES PATENT OFFICE

1,967,457

GUARD FOR TOMATO LUGS AND SIMILAR CONTAINERS

James W. Trew, Gettysburg, Pa., assignor to Rice, Trew & Rice Co. Inc., Biglerville, Pa., a corporation of Pennsylvania

Original application November 7, 1933, Serial No. 697,077. Divided and this application April 19, 1934, Serial No. 721,397

6 Claims. (Cl. 217—3)

This is a specification, reference being had to the accompanying drawing; a division of my pending application Serial No. 697,077, filed November 7, 1933:

5 This invention relates to guards for tomato lugs and similar containers, and it is an object of the invention to provide a device of this kind which when applied has a portion substantially closing the space between a side wall of the lug 10 and the applied lid whereby the upper or facing layer of the tomatoes or the like is effectively protected and wherein the guard is provided with means for direct coaction with the content of the lug or container to facilitate the maintenance 15 of the guard in applied or working position.

The invention consists in the details of construction and in the combination and arrangement of the several parts of my improved guard for a tomato lug or similar container whereby 20 certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

30 Figure 1 is a fragmentary view partly in transverse section and partly in elevation showing a guard constructed in accordance with an embodiment of my invention in applied position;

Figure 2 is a view in elevation of the guard 35 as comprised in Figure 1;

Figure 3 is a view in perspective of a guard constructed in accordance with another embodiment of my invention;

Figure 4 is a view in perspective of a still further embodiment of the invention.

40 As disclosed in the accompanying drawing, the guard comprises an initially flat elongated band B, the outer or upper edge a of which being disposed on an arc to closely approach the general curvature of a lid or cover applied to the lug L. This lug L is of a conventional type employed in the packing of tomatoes and kindred articles and wherein each end wall 1 is secured along its upper edge a cleat 2 which extends a slight 45 distance inwardly of the lug whereby is provided an underlying shoulder 3.

The band B at its extremities is provided with the flaps 4. Each of these flaps 4 is positioned intermediate the ends of the adjacent edge of 55 the band B and is adapted to engage under a

shoulder 3 of the lug L when the band B is in applied or working position. As the band B is applied each of the flaps 4 will be flexed inwardly of the lug.

As particularly illustrated in Figure 2, the band 60 B has its inner or lower edge b substantially straight from end to end and in parallelism with the longitudinal axis of the band.

A desired distance between said straight edge b and the flaps 4 the band B is provided there- 65 along with a score line 5 substantially in parallelism with the straight edge b. The portion of the band B outwardly of the score line 5 is adapted to be folded along such line to provide a laterally directed flange or ledge 6 as particu-

70 larly illustrated in Figure 1, and when the band B is in applied or working position within the lug or kindred container the upper layer of tomatoes or other articles contacts from above with this flange or ledge 6 whereby the contents 75 of the lug or kindred container coact with the applied guard to provide a means for holding the band B in desired placement.

In the invention as illustrated in Figure 3, the band B' along its inner or lower marginal portion is provided with a series of longitudinally spaced slits 7 extending inwardly and transversely of the band B' for a desired distance. The portions of the band B' between certain of the slits 7 are adapted to be folded into a position laterally of the band B' whereby a series 80 of flanges or ledges 8 are provided for coaction with the contents of the lug or kindred container as just explained with reference to the flange or ledge 6 of the band B. Initially these flanges or 85 ledges 8 are coplanar with the band B' proper and each of the portions of the band which is folded outwardly to provide a flange or ledge 8 is further defined by a longitudinal score line 9 along which the flange or ledge 8 is bent.

In the embodiment of the invention as illustrated in Figure 4, the flanges or ledges 10 are cut out within the field of the band B'' so that when the flanges or ledges 10 are extended into working position the resultant openings 11 are entirely enclosed. These flanges or ledges 10 are also initially coplanar with the band B'' and when extended into working position each of these flanges or ledges 10 is bent on a suitably positioned score line 12.

100 From the foregoing description it is thought to be obvious that a guard for a tomato lug or similar container constructed in accordance with my invention is particularly well adapted for use by reason of the convenience and facility with 105 110

which it may be assembled and operated, and it will also be obvious that my invention is susceptible of some change and modification without departing from the principles and spirit 5 thereof and for this reason I do not wish to be understood as limiting myself to the precise arrangement and formation of the several parts herein shown in carrying out my invention in practice except as hereinafter claimed.

10 I claim:

1. A fruit guard comprising a band adapted to be arranged along the upper inner end of a side wall of a container to extend above said side wall to bridge the space between the upper edge of 15 said side wall and an applied lid, and means on the band between the ends thereof and extending laterally from the band for contact with the content of the container to hold the band in applied position.

20 2. A fruit guard comprising a band adapted to be arranged along the upper inner end of a side wall of a container to extend above said side wall to bridge the space between the upper edge of said side wall and an applied lid, and means on the band between the ends thereof and extending laterally from the band for contact with the content of the container to hold the band in applied position, said means being adjacent to the lower or inserted marginal portion 25 of the band.

30 3. A fruit guard comprising a band adapted to be arranged along the upper inner end of a side wall of a container to extend above said side wall to bridge the space between the upper edge 35 of said side wall and an applied lid, and means

on the band between the ends thereof and extending laterally from the band for contact with the content of the container to hold the band in applied position, said means embodying a flange to extend inwardly of the container and to engage the content of the container.

80

4. A fruit guard comprising a band adapted to be arranged along the upper inner end of a side wall of a container to extend above said side wall to bridge the space between the upper edge of said side wall and an applied lid, and a laterally disposed part carried by the lower portion of the band intermediate its ends to extend inwardly of the container to engage the content of the container.

85

5. A fruit guard comprising a band adapted to be arranged along the upper inner end of a side wall of a container to extend above said side wall to bridge the space between the upper edge of said side wall and an applied lid, and a flange carried by the lower portion of the band and extending substantially from one end thereof to the other, said flange extending inwardly of the container to engage the content of the container.

90

6. A fruit guard comprising a band adapted to be arranged along the upper inner end of a side wall of a container to extend above said side wall to bridge the space between the upper edge of said side wall and an applied lid, and a plurality of flanges on the lower portion of the band and spaced apart longitudinally thereof, said flanges extending inwardly of the container to engage the content of the container.
